Frank J. Kuenzl, Deerfield, Ill., assignor to Skil Corporation, Chicago, Ill., a corporation of Delaware

Filed Oct. 7, 1960, Ser. No. 62,426

Term of patent 14 years

(Cl. D93—3)

Fig. 2

Fig. 1 is a perspective view looking toward one side of a hand-operable power saw showing my new design;

Fig. 2 is a slightly reduced top plan view thereof;

Fig. 3 is a slightly reduced side elevational view looking toward the opposite side of the saw from that shown in Fig. 1;

Fig. 4 is a slightly reduced rear end elevational view thereof; and

Fig. 5 is a slightly reduced front end elevational view thereof.

I claim:

The ornamental design for a hand-operable power saw, substantially as shown.
